ISAAC BLUM, OF BALTIMORE, MARYLAND

CULINARY PACKAGE

Application filed January 11, 1932. Serial No. 586,053.

This invention relates to a culinary package.

An object of the invention is to provide a culinary package containing the culinary material such as tea by a very simple and economical process of manufacture.

A further object is to make a package of this character by simple folding operations on a piece of loosely woven fabric or similar material with a minimum amount of sewing to completely form and enclose the material in the package.

A further object is to provide a culinary package containing tea or similar material and providing ample room for expansion of the material during process of infusion.

A further object is to provide a process for making a package of this character which consists in folding a piece of fabric so as to form a sack or package for the reception of the culinary material and requiring to be sewed or stitched merely along one edge of the package in a straight line.

Referring to the drawing, which is made a part of this application and in which similar reference characters indicate similar parts.

Fig. 1 is a plan view of a piece of fabric of generally rectangular form from which the package is made,

Fig. 2 is a plan view of the fabric shown in Fig. 1 folded along a middle line,

Fig. 3 shows the same fabric with the free edges folded back on the main portion of the fabric.

Fig. 4 is a view of the folded fabric made by folding the construction shown in Fig. 3 along its middle line, and

Fig. 5 shows the complete package containing the culinary material with a tag attached thereto by means of a cord or other flexible attaching means.

While the package of this invention is primarily intended as a container for brewing tea it may nevertheless be used for coffee or other similar material. Since devices of this character are made up for individual use and contain only sufficient tea usually to make a single cup or pot of tea it follows that an extremely large number of such packages is

consumed by the public daily. It becomes desirable therefore to make up these packages as cheaply as possible and with that end in view the device of this invention is made up by simply folding a piece of fabric such as cheese cloth or other loosely woven material in such form as to provide a pocket or package for holding the tea or similar material and then running a single straight line of stitching across the one and only open end of the folded package.

According to this invention a new process of folding has been provided. Considering Fig. 1 which shows a piece of fabric such as cheese cloth the process comprises folding the fabric which is rectangular in shape and preferably square along a middle line as indicated at 2-2. This step of folding provides the arrangement shown in Fig. 2 of the drawing where the fabric is shown as doubled about its center line. The next step is to fold the two free edges of the fabric which are parallel to the line 2-2 along the line 3-3. The width of the folded over portion of the free edges of the fabric is preferably about one-third of the width of the doubled fabric. After the second folding operation the fabric has the appearance shown in Fig. 3 wherein the folded edges are shown as covering substantially one half of the sack. The next step is to fold the article as shown in Fig. 3 about its middle line 4-4 forming a construction such as that indicated in Fig. 4.

When the fabric has been folded as indicated in Fig. 4 the tea or other material to be treated is inserted between either of the outside walls of the sack and the other layers of the fabric. In this figure the material may be inserted between the top layer 9 and the immediately adjacent under layer 10. It will be apparent from the manner of folding that two pockets will be formed in the construction as shown in Fig. 4 one on either side of the container. Either of these pockets may receive the tea since they are identical in construction. In folding the fabric which obviously may be done by hand the pocket for reception of the tea may be opened by hand or by any other suitable means so that the tea may be inserted therein. In manu-

facturing the device by machinery a form which is used during the folding operation as indicated in Figs. 2 and 3 may be employed to spread the side pocket of Fig. 4 for the insertion of a filling material.

After the material has been inserted in one of the side pockets of the device as indicated in Fig. 4 the open end of the device may be closed by stitching across as indicated 10 at 11 in Fig. 5. This figure also shows the right-hand end of the package enlarged by reason of its being filled with the filling material such as tea. The quantity of tea used in each individual package is that customarily used in the ordinary tea package or tea ball and the size of the fabric for each package is chosen so that when the material is folded in the manner indicated and the tea inserted the package or bag will not be 15 filled for more than about two-thirds of its length. This is clearly indicated in Fig. 5. This is very desirable since it is well known that tea leaves when placed in hot water will swell and the bag is so constructed as not 20 to necessarily restrict the swelling operation of the tea leaves and thereby prevent the complete infusion. This package provides sufficient space for swelling of the leaves and does not bind when the package is left in 25 the water the necessary time to properly extract the essence of the tea.

It will be apparent from the construction described that the tea leaves are not restricted in expansion by reason of the fact that sufficient space is provided in the sack for the 30 normal expansion and also that one side of the sack is capable of slight opening to permit the full expansion of the leaves without restriction. This is due to the fact that the 35 sack is folded with its free edges turned in on one side and is only stitched across the open end of the sack. This characteristic is indicated by the slight opening of the sides of the sack as indicated at 12 in Fig. 5. There 40 are no free or frayed edges of the material left in position to come into contact with the water when the sack is placed therein. The 45 free edges are folded in and the frayed edges of the end of the sack are protected by the 50 line of stitching running across the end. The 55 usual tag 8 is attached to the bag by means of a string or cord 7 as indicated in Fig. 5 or it may be attached by means of a clip or staple. In Fig. 5 the thread is knotted at one 60 end and is run through the bag and attached to the tag. The manner of attachment of the tag is not essential to this invention.

In the device as illustrated the package is shown as substantially twice as long as it is 65 wide. This is due to the fact that a substantially square piece of fabric is employed in its manufacture. The package might of course be made square in its finished form if fabric of a suitable form is employed in the 70 making. It is considered however of advan-

tage to make the package in the form shown since this construction provides a substantially long bag which is only partly filled by the tea and for the further reason that it requires very little sewing to close the open 75 end. Bags of this character have been made heretofore but all of them required stitching along at least two sides or along a curved line. This obviously slowed up the operation 80 of manufacture since they are usually made by machines which sew in a straight line or the article is necessarily passed under the machine in a straight line and in the constructions referred to the sewing necessitating a turning movement of the bag either continuously for a curved line or one or more right-angle turns for the rectangular form of sack. By folding the material in the manner disclosed herein only one sewing operation is 85 necessary and that is always in a single straight line and comparatively short with respect to the length of the package. It therefore follows that this particular package may be more quickly sewed than those 90 heretofore known and the time of manufacture is materially shortened. This is a matter of great importance in manufacturing devices of this character which must be made in enormous quantities, and it is clear that 95 any saving in the time of manufacture either by simplicity in the construction of a container or in saving time in closing the container is of great importance.

Having thus fully described my said invention, what I claim as new and desire to 100 secure by Letters Patent is:

1. A tea bag comprising a rectangular piece of fabric folded upon itself and having its two free edges folded back upon the body portion, the folded piece being again folded midway of its length on a line at right angles to the first fold line with the free side edges inside, a quantity of tea inserted between one outer fold and the other folds and said bag having a line of stitches across its free end to close the bag.

2. A tea bag comprising a fabric strip folded upon itself and having its two free edges folded back upon the body portion, the piece being again folded about its middle in a line at right angles to the first fold line with the free edges inside, a quantity of tea inserted between one outer fold and the other folds and means for closing the open end of the bag.

In testimony whereof, I affix my signature.
ISAAC BLUM.
